* cited by examiner

Primary Examiner — Susan Bennett Hattan*Assistant Examiner* — Janice Hallmark(74) *Attorney, Agent, or Firm* — Christopher J. Vandam, PA;
Chris Van Dam(57) **CLAIM**

The ornamental design for an atomizer, as shown and described.

DESCRIPTION

FIG. 1 is a three-dimensional exploded view of an atomizer showing my new design;

FIG. 2 is an elevation view thereof;

FIG. 3 is another elevation view thereof;

FIG. 4 is a top plan view thereof;

FIG. 5 is a bottom plan view thereof;

FIG. 6 is exploded elevation view thereof, shown for clarity of disclosure;

FIG. 7 is a three-dimensional view thereof;

FIG. 8 is another three-dimensional view thereof;

FIG. 9 is another exploded three-dimensional view thereof; and,

FIG. 10 is a three-dimensional view of an isolated component of the atomizer of FIG. 1 shown for clarity of disclosure.

An atomizer for use with a personal vaporizer.
